UNITED STATES PATENT OFFICE.

CARL MARTIUS, OF BERLIN, GERMANY.

PROCESS OF PRODUCING A BASIC COLORING-MATTER FROM XYLIDINE.

SPECIFICATION forming part of Reissued Letters Patent No. 10,353, dated July 10, 1883.

Original No. 268,113, dated November 28, 1882. Application for reissue filed June 9, 1883.

To all whom it may concern:

Be it known that I, CARL MARTIUS, of the city of Berlin, of the Kingdom of Prussia, Germany, have invented a new and useful Process 5 for Producing a Basis for Coloring-Matter; and I do hereby declare the same and the mode of making it to be described in the following specification.

In carrying out my invention I, in a closed 10 digester, heat to 280° centigrade hydrochlorate of xylidine with a quantity of methylic alcohol. The crude hydrochlorate of cumidine obtained in that way I convert into the nitrate, which, being soluble with difficulty, I 15 separate from the mother-liquors by means of a centrifuge, and wash with water. A fine crystalline powder of nitrate of cumidine is thus obtained. This nitrate is next to be converted into the base and subjected to fractional 20 distillation. The parts boiling between 225° and 245° centigrade crystallize on cooling. The crystals are next to be separated from the non-crystallizable mother-liquors by means of a centrifuge or a press.

The crystallized cumidine thus obtained has 25 a constant boiling-point of 235° to 236° centigrade, and melts at 62° centigrade, and can be advantageously used in the manufacture of azo colors. It is especially valuable, as its 30 diazo compounds give, with the disulpho-acid of beta-naphthol, colors which are considera-

bly superior in redness to similar products at present on the market. Another orange-red color is obtained by the combination of the diazo compound of the crystallized cumidine 35 with the monosulpho-acids of beta-naphthol.

This cumidine is easily converted into a sulpho-acid by means of sulphuric acid, according to the process already well known in manufacturing sulphonilic acid. The diazo compound of the sulpho-acid of the cumidine likewise produces colors with naphthol.

I claim as my invention as follows:

The process, substantially as described, for producing the new basis for obtaining coloring-matter—viz., crystallized cumidine—such consisting in treating with methylic alcohol in a digester hydrochlorate of xylidine, converting the crude hydrochlorate of cumidine obtained in that way into the nitrate, and by a 40 centrifuge, or other suitable means, separating the resulting nitrate from the mother-liquors, washing it, and subsequently converting it into the base and subjecting it to fractional 45 distillation, and crystallizing the distillate and separating the crystals from the mother-liquors by a centrifuge or other suitable means, all being essentially as explained.

CARL MARTIUS.
